PLANTER OR THE LIKE

Malcome Van Ike, North Hollywood, Calif.

Application May 10, 1954, Serial No. 30,383

Term of patent 14 years

(Cl. D35—3)

FIG. 1

FIG. 2

I claim:

The ornamental design for a planter or the like, substantially as shown.
